UNITED STATES PATENT OFFICE.

EARL H. RICHARDSON, OF ONTARIO, CALIFORNIA, ASSIGNOR TO PACIFIC ELECTRIC HEATING COMPANY, OF ONTARIO, CALIFORNIA, A CORPORATION OF CALIFORNIA.

COMBINATION ELECTRIC HEATER.

1,006,129.

Specification of Letters Patent. Patented Oct. 17, 1911.

Application filed November 9, 1909. Serial No. 527,102.

To all whom it may concern:

Be it known that I, EARL H. RICHARDSON, a citizen of the United States, residing at Ontario, in the county of San Bernardino and State of California, have invented a new and useful Combination Electric Heater, of which the following is a specification.

This invention relates to an electric heater device which is so constructed as to include and combine several different functions in its embodiment, whereby it may be employed as an electric laundry iron, or as an electric stove, or as an electric water heater, or as an electric curling iron heater, and so constructed that the parts may all be nested together in compact form when not in use and form a light, portable appliance of general utility, which is especially adapted for travelers, for use in hotels or apartments or in the household.

Other objects and advantages will be brought out in the following description.

Referring to the drawings:—Figure 1 is a perspective view showing the parts of the device nested together in compact form for carrying. Fig. 2 is a perspective view in detail of the stand. Fig. 3 is a side elevation, partly in section, of the combination heater arranged for heating water or cooking. Fig. 4 is a side elevation of the sad iron in vertical, longitudinal section. Fig. 5 is an enlarged plan view of the lower portion of the iron with the upper parts removed. Fig. 6 is a cross section on the line x^6-x^6 Fig. 4. Fig. 7 is a perspective view of the handle for the water receptacle. Fig. 8 is a side elevation of the iron showing the same resting on the guard.

The stand comprises a dished triangular plate 1 having three legs 2 riveted or otherwise secured at each corner to plate 1, the legs 2 extending slightly above the plate 1, thus forming retaining lugs 3, as clearly shown in Fig. 2, the legs 2 being riveted to the flange 4 on the plate 1. The plate is formed with a longitudinal recess 6 which is enlarged at 7 serving to receive the bail and terminal guard of the sad. iron, as will be described.

8 designates the dish, also of triangular form, as shown in Fig. 1, and of a size adapted to fit within the flange 4 of the plate 1 when the latter is inverted, as shown in Fig. 1. As indicated in Fig. 3, the bot-

tom 9 of the dish is secured by a bead 10 to the side walls which forms a depression with a surrounding flange which is adapted to fit over the sole of the sad iron or to receive the cover 11, as will be described. The cover 11 comprises a flat plate with a depending flange 12 which is adapted to fit within the upper edge of the dish 8 and be retained therein. The rear wall of the dish 8 is provided with a loop 13 which is adapted to receive either foot 14 of a handle 15, the opposite foot 14 acting as a brace to support the dish when lifting it by means of the handle, both feet 14 being similar in construction and oppositely arranged. The handle may be readily connected or disconnected with the loop 13.

The sad iron 16 is adapted to be placed inside of the dish 8, as indicated in Fig. 1, and the dish 8 and stand 1 are of a shape which conforms to the triangular shape of the sad iron, so that all three can be nested together, as shown in Fig. 1, and thus occupy a minimum space when packed. The sad iron 16 comprises a bottom plate or body 17 which is formed with a large triangular recess 18, as shown in Fig. 5, with an extra metal portion 19 in the toe and with extra metal portions 20 in the heel corners. Arranged in the recess 18 and diverging rearwardly are two wire-wound heat conducting cores 21, the front ends of which have tongues 22 with circular heads 23 which are received in correspondingly shaped recesses in the toe 19, so that heat is conducted by the cores 21 directly to the toe portion 19, thereby delivering a greater amount of heat to the toe portion than to the center of the iron where the heat is not so much needed. The heat is generated by means of coils of resistance wire 24 wound on the cores 21. As shown in Fig. 4, sheets of insulation 25 are arranged above and below the wire-wound cores and the cores 21 are made flat and suitably insulated from the wire wound on them. Secured above the body 17 is a pressure plate 26, the front end of which is secured by a very large brass screw 27 to the toe 19, the purpose of the large brass screw 27 being to supply a good heat conducting material in the toe in place of the metal drilled out to receive the screw. An ordinary steel screw and one of the ordinary size would not answer this

purpose nor give as good a heat conducting connection between the toe 19 and pressure plate 26 as this large brass screw 27. Being large the screw 27, although of brass, is sufficiently strong. The pressure plate 26 has a longitudinal cylindrical chamber 28 which is open at the rear end and adapted to receive a curling iron 29, as indicated by dotted lines in Fig. 4, so that whenever it is desired to heat a curling iron all that is required is to simply slip the curling iron in the cavity 28.

Inclosing the pressure plate 26 is a cover 30 which is secured by screws 31 to the pressure plate 26. The screws 31 also serve to attach a bail 32, the latter being supported slightly above the face of the cover 30 by annular ribs 33 pressed up in the metal of the cover 30. The bail 32 supports a handle 34. The rear end of the cover 30 is formed with a raised and inclined boss 35 in which is secured two terminal blades 36 which are insulated from the cover by bushings of insulation material 37. The respective terminal blades 36 are electrically connected with the respective coils of wire 24 and the blades are protected by a guard strap 38 which is secured to the bail 32. The guard 38 acts also as a support for the connection plug shown in dotted lines in Fig. 4, thus taking the strain off the terminal blades 36 and also acting as a support to enable the iron to be tipped up on end as shown in Fig. 8. The cover 30 at the rear end is provided with an orifice 39 which registers with the chamber 28 to permit the insertion of the curling iron 29.

The parts are shown in Fig. 1 packed together for storage. When it is desired to cook, the stand is inverted, as shown in Fig. 3, the sad iron is then inverted and its bail 32 slipped into the recess 6, the guard strap 38 being received in the recess 7. Then the dish 8 is placed on the bottom of the sad iron with the flange 10 fitting the edge of the sad iron, so that the dish is securely held in perfect alinement with the sad iron, so that all of the heat from the iron is applied to the entire bottom of the dish. The flange 10 also prevents the dish from slipping off. The cover 11 is placed on top of the dish and the handle 15 secured by inserting one of the feet 14 inside of the loop 13. By means of the handle 15 the dish may readily be lifted off from the sad iron and handled. When the iron is inverted as shown in Fig. 3 it obviously acts as an electric stove and is capable of heating other things or dishes other than the dish 11 by removing the latter. If at any time it is desired to heat a curling iron, the curling iron may be slipped into the chamber 28, for which purpose it is obviously not essential that the sad iron be inverted and supported by the stand, as indicated in Fig. 3, as the

sad iron could stand right side up supported on either the stand or any other convenient support.

What I claim is:

1. In a combination electric heater, a body, electric heating means therein, said body having an external heating surface, a stand comprising a plate with legs secured thereto and projecting slightly on one side of the plate forming lugs to receive and hold the body against slipping, a dish shaped to fit between said legs or lugs, the body being shaped to fit within said dish. 70

2. In a combination electric heater, a body, electric heating means therein, said body having an external heating surface, a stand comprising a plate with legs secured thereto and projecting slightly on one side of the plate forming lugs to receive and hold the body against slipping, a dish shaped to fit 80 between said legs or lugs, the body being shaped to fit within said dish. 85

3. In a combination electric heater, a body, electric heating means therein, said body having an external heating surface, a stand comprising a plate with legs secured thereto and projecting slightly on one side of the plate forming lugs to receive and hold the body against slipping, a dish shaped to fit 90 between said legs or lugs, the body being shaped to fit within said dish, a bail and handle on the body, said plate having a slot to receive said bail. 95

4. In a combination electric heater, a body, electric heating means therein, said body having an external heating surface, a stand comprising a plate with legs secured thereto and projecting slightly on one side of the plate forming lugs to receive and hold the body against slipping, a dish shaped to fit 100 between said legs or lugs, the body being shaped to fit within said dish, a bail, handle and terminal guard on the body, said plate having a slot to receive said bail and an enlarged opening to receive said terminal 110 guard. 105

5. In a combination electric heater, a body, electric heating means therein, said body having an external heating surface, a stand comprising a plate with a flange around its 115 edge, legs attached to said flange and projecting slightly from the side of the plate opposite the flange forming lugs to receive and hold the said body against slipping, a dish shaped to fit within said flange, and a 120 handle and bail on said body, said plate having a slot adapted to receive said bail. 125

6. In a combination electric heater, a body, electric heating means therein, said body having an external heating surface, a stand comprising a plate with a flange around its edge, legs attached to said flange and projecting slightly from the side of the plate opposite the flange forming lugs to receive 130 and hold the said body against slipping, a

dish shaped to fit within said flange, a handle and bail on said body, said plate having a slot adapted to receive said bail, said dish having an external flange fitting over the 5 edge of the heating surface of said body.

7. In a combination electric heater, a body, electric heating means therein, said body having an external heating surface, a stand comprising a plate with legs secured thereto 10 and projecting slightly on one side of the plate forming lugs to receive and hold the body against slipping, a dish shaped to fit

between said legs or lugs, the body being shaped to fit within said dish, a loop in said dish, and a handle with a foot adapted to 15 detachably engage said loop.

In testimony whereof, I have hereunto set my hand at Ontario, California, this 30th day of October, 1909.

EARL H. RICHARDSON.

In presence of—

C. V. SMITH,
EDWIN CRAMER.
